UNITED STATES PATENT OFFICE.

DOMENICO LUIS HENDRIKUS CAFFERATA, OF ROTTERDAM, NETHERLANDS.

FUEL PUMP FOR INTERNAL-COMBUSTION ENGINES.

Application filed March 20, 1924, Serial No. 700,684, and in Netherlands May 11, 1923.

The present invention relates to improvements in a fuel pump for internal combustion engines, in which the difference in pressure in the compression space acts on a differential piston, which is connected to the plunger of the pump.

I am aware, that a fuel pump has already been designed, whereby the movement of the plunger results of the difference in pressure in the compression space. This pressure is transmitted to a differential piston, which is connected to the plunger, whilst the pressure valve is a spring controlled needle valve. This pump however needs a mechanical drive.

The pump according to the invention works quite automatically and needs no cams nor eccentrics and can be readily attached to any cylinder by means of a projection, which is a part of the pump, containing the fuel-delivery channel.

For this reason, the invention is particularly suitable to be applied when reconstructing a steamship into a motorship and re-employing a part of the existing plant, such as the crankshaft.

The invention is illustrated in the accompanying drawings in which—

Fig. 1 is a section lengthwise,

Fig. 2 a section of a part of the pump according to another form of construction, and

Fig. 3 a section of another form of construction of the pump.

The fuel pump is provided with a threaded or flanged projection 1, with which it can be screwed or attached on a cylinder-head and consists of a cylindrical body 2, which is bored lengthwise. In this bore, there are two plungers, one of which is the smallest plunger of a differential piston 3, the other one being a needle-valve 7. The larger plunger of the differential piston is situated in a bore 4, which communicates with the combustion space of the cylinder by means of a channel 5. The surface of the last mentioned plunger equals about ten times that of the smallest one; thus the pressure in the compression space is increased tenfold when transmitted by the differential piston. The needle valve 7 is provided with an adjustable spring 6, which presses the valve on its seat, said valve when being lifted by the pressure of the fuel situated between the two plungers, uncovers the channel 8 made in the projection 1 and leading to the spraying nozzle. The fuel-feeding device comprising an inlet pipe 9, a valve 10 and a non-return valve 11. The differential piston and its spring are cooled by a liquid lead through the ports 12. The channel 5, may also be made in the projection 1 as shown on Fig. 3 of the drawings. This makes assembling particularly easy and moreover diminishes the possibility of leaking.

Instead of leading the fuel in the space between the plungers 3 and 7, this can be done such as indicated in dash-line on Fig. 1. The fuel-inlet is located remote from the end of the plunger 3 and this plunger is provided with a radial and an axial bore 13 respectively 14 (Fig. 2) whereby the latter contains a non-return valve 15.

The working of my fuel pump is as follows:

The fuel entering at 9 passes the valve 10, which serves to control the quantity of fuel admitted, and comes into the space between the plungers 3 and 7. At the compression stroke, the pressure in the cylinder increases and this pressure is transmitted through the channel 5 to the space 4, where it acts on the piston 3, and is transmitted further tenfold to the fuel situated between the plungers. The pressure of this fuel shall amount to 250-300 atm. The non-return valve 11 resp. 15 prevents the fuel from escaping through the inlet valve. The tension of the spring 6 is regulated in such a manner, that the needle-valve is lifted at the moment the cylinder piston has nearly reached its upper dead centre. Thus a quantity of fuel is pressed through the channel 8 to the spraying nozzle and into the cylinder at a predetermined moment, which can be exactly regulated by means of the spring 6. When the pressure in the cylinder decreases, the needle-valve is closed and the differential piston will be moved to the right by the effect of its spring, thereby drawing a quantity of fresh fuel into the pump. By the form of construction according to Fig. 2, the fuel can only flow into the channel 14 at the moment that the channel 13 corresponds with the exhaust of the valve 10.

These fuel pumps can be used for two- or four-stroke combustion engines with one or a plurality of cylinders.

I claim:

An automatic fuel supply pump and injection device for internal combustion engines comprising a body having axially aligned and communicating bores leading

from opposite ends thereof and provided on one side with a projection by means of which the body may be attached to an engine cylinder, a differential piston arranged in one of 5 said bores of the body, a duct extending through said projection and said body to the outer side of the greatest diameter of said piston, so that said piston is in constant communication with the combustion space 10 of the cylinder through said duct, a spring active to move said piston outwardly, a fuel supply duct leading to the bore of the differential piston and having fuel supply regulating means, a needle valve in the other 15 bore and having its outer end arranged at the end of said body opposite that in which the greatest diameter of the differential pis-

ton is arranged, a spring active to momentarily hold the needle valve in closed position, and a duct leading from the bore in 20 which the needle valve operates through said projection, so that both the duct which puts the combustion space of the cylinder in communication with the outer side of the largest diameter of the piston and the duct through 25 which fuel is supplied to the cylinder are both arranged in the same projection and the outer ends of the differential piston and needle valve are accessibly located at opposite ends of the body.

In testimony whereof, I have signed my name to this specification.

DOMENICO LUIS HENDRIKUS CAFFERATA.
